UNITED STATES PATENT OFFICE

2,591,305

HANDLE FOR SUCTION CLEANER CASING

Louis E. Segezman, Canton, Ohio, assignor to
The Hoover Company, North Canton, Ohio, a
corporation of Ohio

Application August 15, 1946, Serial No. 690,706

2 Claims. (Cl. 220—94)

1

The present invention relates to suction cleaners and more particularly to a carrying handle for a suction cleaner.

An object of the invention is to provide a new and improved suction cleaner. Another object is to provide an end cap for a suction cleaner casing, the end cap having a handle for carrying the cleaner. A further object is to provide a suction cleaner end cap having a handle recessed therein for carrying the cleaner. Other objects and advantages of the invention will be apparent from the following specification and drawings wherein:

Figure 1 is a broken longitudinal section of the cleaner;

Figure 2 is a bottom plane view of the handle in the front end cap; and

Figure 3 is a section of a modified handle in the cleaner front end cap.

The embodiment of the invention disclosed in Figures 1 and 2 comprises a casing 10 closed at its exhaust end by a cap 11 having an outlet port 12 adapted to receive the cleaner end of an unshown dusting tool hose provided at its opposite end with a surface-cleaning tool in a manner well known in the art. The end surface 13 of the cap 11 extends normal to the longitudinal axis of the casing 10 so that the latter may be stored in a vertical upended position by placing the end cap 11 on a supporting surface.

The suction end of the casing 10 is closed by a removable end cap 14 provided with an inlet port 15 adapted to receive the cleaner end of a dusting tool unit in the same manner as port 12. The end cap 14 is removably attached to the casing 10 by being provided at its lower end with a protruding lip 16 which seats within a pocket 17 formed at the end of a bracket 18 mounted on the flat bottom wall 19 of the casing 10. A latch 20 is mounted on the top of the casing 10 and cooperates with the end cap 14 to force it against the end wall 21 of the casing 10, and a seal 22 prevents leakage of air therebetween.

Within the casing 10 adjacent the rear end cap 11 is a motor 23 for driving suction-creating fans disposed in a fan chamber 24. Between the fan chamber 24 and the front end cap 14 is a filter bag 25 having a closed end wall 26 and an open end which is secured to a circular flange 27, the latter defining the inlet to the bag 25. The casing 10 is slidably supported in horizontal position for its surface-cleaning operation by a pair of skids 28 attached to the casing 10.

A carrying handle 30 is provided in the front

2

end cap 14 and includes a recess 31 formed in the flat bottom portion 32 of the side wall 33 of the end cap 14, and the front wall 34 of the end cap 14 forms part of the recess 31. The recessed handle 30 is spaced from the supporting surface by the skids 28 to permit the operator to insert his hand between the end cap 14 and the supporting surface to grasp the front end cap 14 to lift the cleaner and carry the latter from place to place.

When the cleaner is in its storage position the longitudinal axis of the casing is vertical and the rear end cap 11 rests upon the supporting surface with the handle 30 spaced upwardly from the supporting surface at a convenient height for the operator to grasp the handle. In carrying the cleaner the operator places his fingers in the recess 31 and grasps the handle 30 in the front end cap 14, and in placing the cleaner on its skids 28 there is provided sufficient space between the end cap 14 and the supporting surface for the operator to remove his hand from the recess 31.

Figure 3 discloses a modified handle 40 in a front end cap 41 which is attached to the casing 10 in the same manner as the end cap 14. The handle 40 is recessed at 42 into the end cap 41 by an arcuate member 43 and the entrance 44 to the recess 42 is in the front wall 45 of the end cap 41 and is spaced upwardly from the lower wall 46 of the end cap.

In use the operator places his fingers in the recess 42 and his thumb about the front wall 45 and bottom wall 46 whereby the cleaner can be carried from place to place. The position of the recess 42 with respect to the supporting skids 28 provides sufficient space between the cleaner end cap 41 and the skid-supporting surface for the operator to insert his hand to grasp the handle.

I claim:

1. In a suction cleaner, a casing having an opening at one end, a cap removably attached to said casing one end for access to the interior of said casing through said opening, spaced supporting skids on said casing projecting outwardly beyond the bottom surface of said casing and the bottom surface of said cap for engagement with the floor covering to space said bottom surfaces of said casing and cap above the floor covering, and a handle in said cap and comprising a wall means defining a recess extending radially inwardly from the periphery of said cap and having its entrance disposed in said bottom surface of said cap between the limits defined

by said spaced supporting skids, whereby the latter when resting on the floor covering at all times positions said entrance to said handle toward the floor covering for inserting the operator's hand into said handle.

2. In a suction cleaner, a casing having an opening at one end, a cap removably attached to said casing one end for access to the interior of said casing through said opening, spaced supporting skids on said casing projecting outwardly beyond the bottom surface of said casing and the bottom surface of said cap for engagement with the floor covering to space said bottom surfaces of said casing and said cap above the floor covering, and a handle in said cap and comprising wall means defining a recess extending radially inwardly from the periphery of said cap and adjacent to the exposed end wall of said cap for the reception of the operator's fingers in said recess and thumb on said end wall of said cap, said recess having its entrance disposed in the bottom surface of said cap between the limits defined by said spaced supporting skids, whereby the latter when resting on the floor covering at all times positions said entrance to said handle toward the

floor covering for inserting the operator's fingers into said handle and the thumb on said cap end wall.

LOUIS E. SEGESMÁN.
